UNITED STATES PATENT OFFICE.

JAMES F. MOLLOY, OF WEST HAVEN, CONNECTICUT.

BUCKLE.

SPECIFICATION forming part of Letters Patent No. 231,603, dated August 24, 1880.

Application filed April 14, 1880. (No model.)

To all whom it may concern:

Be it known that I, JAMES F. MOLLOY, of West Haven, in the county of New Haven and State of Connecticut, have invented certain 5 new and useful Improvements in Buckles, of which the following is a specification.

My invention consists in the combination, in a double buckle, of two bows, the ends of one of which are bent outward to form teeth for 10 acting in conjunction with the other bow, and the ends of the other of which are closed around the first-mentioned bow to secure the two together, and teeth made separate from either bow and closed around the first-mentioned bow, 15 for acting in conjunction therewith, whereby a simple double buckle is produced comprising only three pieces, and either of which two buckles may be manipulated with the same facility as a single buckle.

20 The invention also relates to certain details of such construction.

In the accompanying drawings, Figure 1 represents, upon an enlarged scale, a face view of one side of a double buckle embodying my 25 invention. Fig. 2 represents, upon the same scale, a similar view of the other or reverse side thereof; and Fig. 3 represents a side view of such buckle constructed so that the teeth of the two buckles close upon opposite sides of 30 their bows.

Similar letters of reference designate corresponding parts in all the figures.

A and B designate the two bows of the double buckle, one of which, B, constitutes the tongue 35 of the other buckle, being provided with the teeth a, formed by bending its ends outward, for acting in conjunction with the bow A. These parts, so far as described, differ in no way from an ordinary form of single buckle, 40 like that, for example, shown in Letters Patent No. 13,218, granted July 10, 1855.

b designates the teeth of one buckle, which act in conjunction with the bow B, and which are here formed in one piece with a tongue, C, 45 but which might be attached to the buckle separately, if desirable. This tongue, like the tongue and bow B, may be, and preferably is, constructed of wire, as when so constructed no metal is wasted in the manufacture, and, as

here shown, the said tongue C is secured in 50 place by being bent to form loops c, which are secured to the tongue B by being closed around the same upon the outside of the teeth a, between said teeth and the ends d of the bow A, which are closed around the tongue portion of 55 the bow B to hold it in place.

As here represented, the teeth a close upon one side of the bow A, while the teeth b close upon the opposite or reverse side of the bow B. This construction enables the two portions 60 D of a single strap, or of two straps, to pass each other, one outside the other, as is clearly shown in Fig. 3, and although here illustrated only in connection with a buckle of my improved construction, this feature of arranging 65 the teeth of a double buckle to close upon opposite sides of the bows is applicable to double buckles of other construction.

By my invention I enable a double buckle to be formed from a single buckle by simply 70 securing thereto the tongue C, provided with teeth b; and this method of construction is very desirable, inasmuch as the principal portions of the double buckle may be formed by the same tools used to shape and connect the parts of a 75 single buckle.

What I claim as my invention, and desire to secure by Letters Patent, is—

1. In a double buckle, the combination of two bows, the ends of one of which are bent 80 outward to form teeth for acting in conjunction with the other bow, and the ends of the other of which are closed around the first-mentioned bow to secure the two together, and teeth made separate from both bows, also closed around 85 said first-mentioned bow for acting in conjunction therewith, substantially as specified.

2. The combination of the bow A, the bow and tongue B, provided with teeth a and secured to the bow A by closing portions d, and 90 the tongue C, provided with teeth b and secured to the bow and tongue B by the loops c, closed around the latter outside the teeth a, substantially as specified.

JAMES F. MOLLOY.
